RUBBER BASED METALLIC SKATE GUARD

Donald F. Condon, Houston, Tex.

Application January 23, 1950, Serial No. 140,041

2 Claims. (Cl. 280—11.38)

1

This invention relates to, and has as an object the providing of, a skate guard which has therein a flexible strip on which the skate may bear; the strip, in turn, resting upon the base and within the base of the skate guard body or housing.

It is a further object of this invention to provide a skate guard of this class having a flexible strip enclosed within a rigid housing.

It is yet another object of this invention to provide a skate guard of this class having a housing which may be made of extruded metal, as aluminum, which is of light weight yet of durable characteristics.

It is still another object of this invention to provide a skate guard of this class in which the teeth of the skate toe rest upon the resilient strip in the prow of the guard.

It is still a further object of this invention to provide a skate guard of this class in which the skate rests upon a flexible strip throughout substantially the entire length of the skate.

It is yet another object of this invention to provide a skate guard of this class in which resiliently adjustable means at the rear end of the flexible strip may be employed to clasp the heel substantially the entire length of the skate.

It is yet a further object of this invention to provide a skate guard of this class in which resiliently adjustable means may be attached to the skate in any of a plurality of positions to clasp the heels of various length skates.

Other and further objects will be apparent when the specification is considered in connection with the drawings, in which:

Figure 1 is a side elevation of one modification of a skate guard;

Fig. 2 is a sectional elevation of the modification shown in Fig. 1;

Fig. 3 is a sectional elevation taken along line 3—3 of Fig. 1;

Fig. 4 is a fragmentary perspective view showing details of construction of the modification of Fig. 1;

Fig. 5 is a fragmentary perspective view showing details of assembly of the modification of Fig. 1;

Fig. 6 is a fragmentary sectional elevation showing details of a second modification of the invention;

Fig. 7 is a plan view, part in section, taken along line 7—7 of Fig. 6.

In skate guards heretofore employed, the body of the skate guard has been made of a flexible element, as leather, which also served as the element which took the wear of contact with the floor or ice. In some of these previous prior art

2

skate guards, a guard has been provided and inserted within the flexible body member, and such guard may have been of metal, as brass or bronze. However, in none of the prior art skate guards has a flexible or resilient element been provided to receive the contact with the skate, and to be inserted within a substantially rigid guard body or housing, as those which may be made of a light metal, as extruded aluminum.

With a skate guard fabricated of such an extruded metal, it is possible to obtain an easily produced, substantially rigid structure of considerable durability, to wear against the floor or ice; and it is also possible to insert therein a flexible element or strip, as of rubber, which can cushion the weight of the body placed on the skate blade, which may be mounted to rest upon the rubber strip. Such a construction provides a more comfortable skate guard than has heretofore been provided, and such a guard also has more durability than those of conventional type heretofore employed.

As shown in Fig. 3, a cross section taken through one modification of my skate guard as shown in Fig. 1, shows a housing or body 1, which may be made, as of extruded aluminum, having the upper sides 2 thereof tapered inwardly and a having a slot 3 formed in the upper portion of the guard, which slot includes and terminates downwardly in an enlarged portion, as an extruded or cored bore 4. Such slot 3 and bore 4 extend from the prow 5 of the skate guard to a point substantially in proximity with the rear end 6 thereof. A rubber cylinder or strip 10, which may optionally be of any other plastic yet durable material, is inserted in the bore 4 to extend as shown in Fig. 2.

A plug or stop 7 may be inserted into the upper end of the prow 5 and held within the skate guard, as by the pin 8 inserted therethrough. As shown in Fig. 2 and more definitely in Figs. 4 and 5, the rear end 6 of the skate guard has a counterbore 11 therein, which is threaded at the extreme outer end 12. To provide a resilient or flexible adjustment to receive the rear end or heel 14 of a skate, the trigger 15 is provided, which comprises the clasp 16 and the cylindrical member 17 having the bore 18 therein. This element may be inserted in the counterbore 11 and slot 3 so that the cylindrical member 17 shoulders at 18' when the spring 19, shown in Fig. 2 but omitted for clarity in Fig. 5, is inserted in the counterbore 11 and held in place by threading the plug 22 into the threaded end 12.

With this construction the heel 14 of a skate 55 20 may be inserted in the guard 1 to bear against

the surface 23 of the trigger 15 and force it rearwardly against the tension of the spring 19. This enables the toe 24 of the skate, having the teeth 25 thereon, to extend to the left of, and above, the skate guard prow 5. Then downward motion of the toe 24 will enable the teeth 25 of the skate 20 to be brought into contact with the flexible strip 10, and the skate will thus be locked and held in position by the force of the spring 19, which contacts the trigger 15 at the base 27 of the trigger bore 18. Then, when a skater, wearing the shoe 30, exerts weight upon the skate 20, this weight is cushioned as it bears upon the strip 10. Such a construction is particularly adapted where skate guards are designed to fit skates of a certain length and configuration, as the custom-made skate 20 shown generally in Fig. 2.

As shown in Figs. 6 and 7, a skate guard 35 may be provided which has no counterbore at the rear end and in which the rubber strip 10 in the bore 4 thereof extends to substantially the extreme rear of the guard, as to the point 37. Holes 38 are provided, in spaced-apart relationship, in the base 39 of the skate guard 35, for a purpose to be hereinbelow described, and these holes are located forward of, and below, the rear end of the flexible strip 10.

The spring 42, which has inserted thereover centrally thereof the rubber sheath or protector 43, is installed on the skate guard 35 by connecting the spring ends 41 to the screws 40 which are threadable into the holes 38. With a skate guard of this design the sheathed portion of the spring 42 is contacted by the heel portion 45 of a skate 46 to extend the spring upwardly and rearwardly until the toe of the skate may be inserted within the prow of the skate guard so that the skate 20 rests upon the rubber strip 10. The provision of several holes 38 will allow the screws 40 to be installed at different points longitudinally along the skate guard base 39 so that the spring 42 may be positioned to receive and clasp skates of various length blades.

Broadly, this invention considers a skate guard construction of a substantially rigid body or housing having therein a flexible strip, as rubber, to be contacted by a skate so as to receive the skate and the weight thereon for flexible support. This invention also considers a novel means of providing adjustable resilient means for clasping a skate blade in the skate guard.

What is claimed is:

1. A skate guard comprising, an elongated, integrally formed, substantially rigid body of uniform cross-section having a prow-shaped forward end, a vertical slot in the upper part of said body and extending for substantially the length thereof and communicating inwardly with a bore of greater diameter than the width

of said slot and extending longitudinally and substantially centrally of said body and having a threaded rear portion, a resilient means filling the body bore through the prow and greater portion of said body, a latch insertable into said slot and bore to the rear of said resilient means and providing a forwardly extending, arcuate under surface and a bore in the lower, rear portion to be positioned substantially co-axially of said body bore, a spring insertable in said body to the rear of said latch so that the forward end of said spring may bear in said latch bore, and a plug threadable into the rear portion of said body bore and against the rear end of said spring to adjust the tension thereof, said skate guard being adapted for latched connection to skates of varying lengths insertable in said slot to be resiliently supported by said resilient means and which skates have serrated forward ends to bear against said resilient means within said prow, and which have downwardly curved rear ends to be yieldably latched by contact with said arcuate under surface of said latch.

2. A skate guard comprising, an elongated, integrally formed, substantially rigid body having a prow-shaped forward end, a vertical slot in the upper part of said body and extending for substantially the length thereof, said slot including a bored rear portion having the rear end thereof threaded, a resilient means extending in said slot and spaced from said threaded end and extending into said prow, a latch insertable in said slot to the rear of said threaded portion and providing a forward extending, arcuate under surface, a spring insertable in said bore to bear at its forward end against said latch, a plug threadable into said bore rear end to bear against said spring to adjust the tension thereof, said skate guard being adapted for latched connection to skates of varying lengths insertable in said slot to be resiliently supported by said resilient means and which skates have serrated forward ends to bear against said resilient means within said prow, and which have downwardly curved rear ends to be yieldably latched by contact with said arcuate under surface of said latch.

DONALD F. CONDON.
